PENCIL-LIKE IMPLEMENT

George D. Nelson, Los Angeles, Calif.

Application January 22, 1945, Serial No. 573,851

5 Claims. (Cl. 120—13)

1

The invention relates to a pencil-like implement for housing, advancing and retracting a stick of material such as a crayon, or eraser of rubber or other material, or, in fact, a stick of buffing material or the like.

An object of the invention is to provide a manually-operable feed mechanism and casing arrangement wherein the stick of material may be almost as long as the length of the implement itself, and wherein the casing of the implement may accommodate a stick which fills a major portion of the bore or casing.

Another object of the invention is to provide such an implement having a feed mechanism which is simple in construction and wherein the device is reversible in that the feed mechanism may be mounted in either end of the casing.

For further details of the invention reference may be made to the drawing, wherein:

Figure 1 is an enlarged, longitudinal sectional view of a pencil-like implement according to the present invention.

Figs. 2 to 6, inclusive, are sectional views on lines having corresponding numbers in Fig. 1.

Fig. 7 is a schematic, longitudinal sectional view of the implement of Fig. 1, enlarged about one and one-half times.

Referring in detail to the drawing, the implement 1 of this invention is shaped somewhat like a pencil and comprises an elongated, cylindrical casing 2 which may be of plastic or other material, and provided with an internal screw thread 3. The thread 3 preferably extends the full length of the casing 2 to effect an economy in assembling the device in that the parts are reversible as will be explained hereafter. At the rear end of casing 2 is provided a rotatable cap 4 in which is secured a central plug 5 having a plug extension 6 which frictionally fits in the bore of the threads 3, to prevent cap 4 and its associated parts from accidentally dropping out. It has been found that this frictional engagement, plus some added friction later described, is sufficient for the purpose, although a more complicated arrangement may be provided, if desired, for rotatably supporting cap 4 in the end of casing 2.

Adjacent the periphery of plug 6 is secured a spindle in the form of a pair of diametrically opposite thin metal strips 7 and 8 which extend substantially parallel to each other for almost the full length of the casing 2. The forward ends of the strips 7 and 8 are suitably secured as by means of solder 9 to a sleeve 10 of thin metal and having an external diameter slightly less than

2

the internal diameter of the thread 3, the inside of ring or sleeve 10 having a bore 11 in which slidably fits the stick 12, which may be an eraser, crayon, buffing stick or the like.

5 Rotatably fitting in the thread 3 is a nut 13 having a mating external thread 14. The nut 13 at diametrically opposite points in its periphery has shallow grooves or recesses 15 and 16, as shown in Fig. 4, to slidably fit and receive the strips 7 and 8, respectively. Integral with the front of nut 13 and arranged between the strips 7 and 8 is a cylindrical sleeve 17 serving as a holder for the rear end 18 of the stick 12. The holder 17 serves to removably hold frictionally or otherwise, the rear end 18 of the stick so that an old stick may be removed and a new one inserted and held therein.

In order to use up as much of the stick 12 as possible, preferably the external diameter of the holder 17 is slightly less than the sleeve 10 so that the nut 13 can be advanced until the holder 17 fits within the sleeve 10.

10 At the front of casing 2 there is provided a tip 19 having a conical wall 20 having a hollow conical bore 21 which converges to an outlet 22 in which the forward end 23 of the stick slidingly fits. The rear end of tip 19 is provided with a reduced section 24 having an external screw thread 25 to fit in the casing thread 3.

15 The parts above-described are reversible, as the tip 19 may be screwed into either end of the casing 2, the plug extension 6 will frictionally engage the thread 3 at either end of casing 2, and the nut 13 may be screwed into the casing 2 at either end thereof. This effects an economy in the manufacture and assembly of the device.

20 The added frictional means which serves to aid in frictionally holding the rotatable cap 4 on the end of the casing may result from frictional engagement between the sleeve 10 and the screw threads 3, resulting from the fact that the metal strips 7 and 8 are quite flexible and due to this and also to accidental connection of these strips to the sleeve 10 out of alignment, the sleeve 10 may, due to spring action of the strips 7 and 8, tend to assume an offset position.

25 By rotating the cap 4 in one direction or the other, the strips 7 and 8 serve to advance or retract the nut 13 and the holder 17 and stick 12 carried thereby.

In effect, a three-point support is provided for the stick 12, as it is supported at its rear end by the holder 17, at an intermediate point by the sleeve 10, and at its forward point by the outlet 22.

The converging conical bore 21 serves to guide the forward end 23 of the stick outwardly through the tip 19.

As shown in Fig. 7, nut 13 may be retracted to the rear end of the casing 2, and the stick 12 may be substantially as long as the casing 2. Also, ring 10 may be thin and large enough to loosely fit in the threaded bore of casing 2, and strips 7 and 8 may be thin and extend close to the threads 3, where the diameter of stick 12 may be more than one-half and, in fact, about three-quarters or more of the internal diameter of bore of threads 3 in the casing 2.

As rubber deteriorates when exposed to the light, and as it may become soiled when handled, both of these defects are overcome in the case that the stick 12 is a rubber eraser, because the casing 2 excludes the light from the eraser and prevents it from becoming soiled.

An ordinary pencil eraser, such as the one usually provided on the end of a lead pencil, tends to creep out of its ferrule or holder when the eraser is in use. This is prevented in the usual case by crimping the holder into the body of the eraser. By actual test of the implement of Fig. 1, it has been found that when employing an elongated rubber eraser for the stick 12, it does not creep out of its holder 17, illustrated as a cylindrical cup, even though the interior wall of holder 17 is smooth, as illustrated. In one of the tests the inside wall of the holder 17 was provided with a partial screw thread to grip the rear end of the eraser, but it was found that this was not necessary. The rear end of the cup-shaped holder 17 may be provided with a rearwardly converging conical portion 26 and the rear end 18 of the eraser 12 may be similarly tapered to fit therein. The reason why the rubber eraser does not creep out of the holder 17 is probably due to the fact that when the eraser is in use, all of the flexing of the eraser takes place either at the outlet 22 or at least between the outlet 22 and the intermediate support provided by the ring 10, whereby there is no lateral flexing or creeping tendency at the holder 17, while the downward pressure on the forward end of the eraser pushes it more firmly in the holder 17. Therefore, it is unnecessary to crimp the holder 17 into the body of the eraser as is ordinarily done with a lead pencil eraser, but instead the holder 17 may constitute means for removably holding the rear end of the eraser which facilitates its insertion and removal.

Various modifications may be made in the invention without departing from the spirit of the following claims. For example, one may dispense with the reversible feature above-described and make the tip 19 integral with the casing 2.

I claim:

1. A pencil-shaped implement for a stick of material, viz., crayon, eraser or the like, said implement comprising a casing having an elongated cylindrical wall, a screw thread on the inside of said wall, a nut in said casing rotatably fitting

said screw thread, said nut having shallow opposed recesses in the periphery thereof, a holder for the rear end of said stick on the forward end of said nut, a rotatable cap on the rear end of said casing, a pair of substantially parallel strips secured at their rear ends to said cap and slidably receiving and fitting said recesses, a ring secured to the forward ends of said strips, said ring having a bore to slidably support an intermediate portion of the stick, the forward end of said casing comprising a conical wall providing a converging bore, the forward end of said conical wall defining an outlet in which the stick slidingly fits, said conical wall serving to guide the stick to said outlet.

2. A pencil-shaped implement for a stick of material, viz., crayon, eraser or the like, said implement comprising a casing having an elongated cylindrical wall, a screw thread on the inside of said wall the full length thereof, a nut in said casing rotatably fitting said screw thread, means on said nut for removably holding the rear end of said stick, a rotatable cap fitting either end of said casing, said cap having a smooth plug portion frictionally fitting in the threaded end of said casing wall at either end thereof, a conical tip providing a converging bore, the rear of said tip having an external screw thread fitting in said casing thread at the other end of said casing, the forward end of said tip defining an outlet in which the stick slidingly fits, said tip having a conical wall serving to guide the stick to said outlet.

3. A pencil-shaped implement according to claim 1, wherein said strips are thin and closely adjacent to said casing thread, said holder, said ring bore and said outlet being constructed and arranged to accommodate a stick having a cross sectional area at least as large as one half of the cross sectional area of the inside of said casing.

4. A pencil-shaped implement for a stick of material, viz., crayon, eraser or the like, said implement comprising a casing having an elongated cylindrical wall, a screw thread on the inside of said wall, a nut in said casing rotatably fitting said screw thread, said nut having a shallow recess in the periphery thereof, a holder for the rear end of said stick on said nut, a rotatable cap on the rear end of said casing, and an elongated strip secured at its rear end to said cap and slidably receiving and fitting said recess, the forward end of said casing having an outlet for the stick.

5. A pencil-shaped implement according to claim 4, wherein said strip is thin and closely adjacent to said casing thread, said holder, and said outlet being constructed and arranged to accommodate a stick having a cross sectional area as large as the major portion of the cross sectional area of the inside of said casing.

GEORGE D. NELSON.
